[57] CLAIM

The ornamental design for a bag, as shown and described.

DESCRIPTION

FIG. 1 is a top, left perspective view of a bag showing our new design;

FIG. 2 is a front elevational view thereof;

FIG. 3 is a rear elevational view thereof;

FIG. 4 is a left side view thereof, the right side view being a mirror image;

FIG. 5 is a top plan view thereof;

FIG. 6 is a bottom plan view thereof;

FIG. 7 is a top, left perspective view of a second embodiment of FIG. 1, the only difference being in the face on the front of the bag;

FIG. 8 is a third embodiment of FIG. 1, the only difference being in the face on the front of the bag;

FIG. 9 is a fourth embodiment of FIG. 1, the only difference being in the face on the front of the bag.
